UNITED STATES PATENT OFFICE.

ROBERT L. LYONS, OF WALTHAM, MASSACHUSETTS, ASSIGNOR TO FREDERICK OSANN COMPANY, OF NEW YORK, N. Y., A CORPORATION OF NEW YORK.

SEWING-MACHINE GUARD.

Application filed April 11, 1924. Serial No. 705,840.

Certain types of power sewing machines are equipped with rotary take-up devices on the outer face of the needle bar housings. The object of this invention is to provide a 5 guard which will eliminate the danger of the operator's hair becoming caught in this take-up device and cause injury as she bends toward the machine to properly see and guide the work. As these machines run at high 10 speed injury from accidental catching of the hair in the take-up mechanism would be likely to be of a serious nature.

In order that the guard shall not inconvenience the operator, it is preferable to form it 15 transparent for the most part so that it shall not hinder her view of the work. It is also so constructed that it may be readily turned out of its guarding position where it extends between the operator's head and the take-up 20 device to a point where she may have ready access to the take-up device when desired.

It is also constructed so that it may be turned from one to the other of these positions and be maintained in the position desired without special thought or care on the 25 part of the operator.

For a more complete understanding of this invention reference may be had to the accompanying drawings in which

30 Figure 1 is a front elevation of the sewing machine showing the guard in operative position.

Figure 2 is an end elevation of the same.

Figure 3 is an elevation of the guard and 35 its mounting detached from the machine.

Figure 4 is a detail section on line 4—4 of Figure 2.

Figure 5 is a detail section on line 5—5 of Figure 4.

40 Figure 6 is a detail section on lines 6—6 of Figures 2 and 4.

Figure 7 is a fragmentary section on line 7—7 of Figure 3.

45 1 indicates the machine frame having an arm 2 terminating in a needle bar housing 3. At the outer face of the needle bar housing is a take-up device comprising a rotating plate 5 having a pivot pin 6 extending therefrom for engagement with the needle thread 50 to effect the take-up action.

The guard attachment comprises a curved plate 10 conforming to the forward edge of the needle bar housing 3 adjacent to its upper end and having its ends turned up in parallel spaced relation as at 11 to form ears to

which may be pivoted mating ears 12 carried by a guard element 13. As shown this guard element preferably comprises a rectangular or other suitably shaped frame 14 holding a piece of transparent sheet material as at 15. 60 In normal operative position this guard 13 extends beyond the face of the needle bar housing in an upwardly and rearwardly inclined position as shown in Figure 1, thus extending between the operator's head and the 65 face of the needle bar housing on which the take-up device is carried. The ears 11 and 12 are pivoted as by means of pivot bolts 18 passing through mating perforations therein and the guard may be swung about these pivots 70 into a position extending substantially parallel to the outer face of the needle bar housing and toward the operator so that the face of the needle bar housing may be readily accessible to the operator when occasion therefor should arise, as for example, when it is desired to lead the thread through the take-up 75 to the needle.

In order that the guard may take either of such positions readily at will without especial thought or care on the part of the operator, provision is made by which it is resiliently centered and held in either of such positions when it is moved theretoward. For this purpose the ears 11 and 12 are formed 80 resilient, and one, herein shown as the ear 11 in Figure 4, is provided with a pair of inwardly extending depressions 16 formed to register at will with a single mating depression 17 in the adjacent ear 12. These depressions 16 register with the depressions 17 when the guard is in either of its desired positions. The ears spring apart sufficiently when the guard is forcibly moved out of one of its positions to permit such movement and to 85 urge the guard into its other position on movement of a sufficient extent theretoward. It will thus be seen that it is only necessary for the operator when changing the position of the guard to forcibly move it from either of 90 its positions toward the other and when the parts are in proper relation it assumes this other position of itself without requiring the operator to exercise any special care.

Having thus described an embodiment of 105 this invention it will be evident to those skilled in the art that various changes and modifications might be made therein without departing from its spirit or scope as defined by the appended claims.

I claim:

1. The combination with a needle bar housing of a sewing machine having a rotary take-up device on its side face, of a guard plate hinged to the forward edge of said housing adjacent to the upper end thereof and movable to and from a take-up guarding position where it extends beyond said face forwardly of said device.
- 10 2. The combination with a needle bar housing of a sewing machine having mechanism on its face, of a guard plate hinged to the forward edge of said housing adjacent to the upper end thereof and movable between a position projecting laterally from said edge beyond the outer face of said housing and said mechanism and a position extending forwardly from said edge.
- 20 3. The combination with a needle bar housing of a sewing machine having mechanism on its face, of a guard plate hinged to the forward edge of said housing adjacent to the upper end thereof and movable between a position projecting from said edge beyond the outer face of said housing and said mechanism and a position extending forwardly

from said edge, and means for resiliently holding said guard plate in one or the other of such positions.

4. The combination with a needle bar housing of a sewing machine, of a plate fixed to the forward edge of said housing and having a pair of outwardly extending spaced ears, a guard member having a pair of spaced ears each pivoted to one of said plate ears, said ears having mating depressions to define resilient stops tending to hold said guard member either projecting beyond the outer face of said housing or projecting forwardly from said forward edge.

5. The combination with a needle bar housing of a sewing machine having a side face with take-up mechanism thereon, of a guard plate hinged to the upper portion of the forward edge of said housing on an axis extending upwardly and rearwardly in a substantially vertical plane, and movable to and from a guarding position where it extends out laterally beyond said side face.

In testimony whereof I have affixed my signature.

ROBERT L. LYONS.
